UNITED STATES PATENT OFFICE.

ALFRED C. HOBBS, OF BRIDGEPORT, CONNECTICUT, ASSIGNOR TO THE UNION METALLIC CARTRIDGE COMPANY, OF SAME PLACE.

MACHINE FOR UNCAPPING CARTRIDGE-SHELLS.

SPECIFICATION forming part of Letters Patent No. 242,775, dated June 14, 1881.

Application filed February 17, 1881. (No model.)

To all whom it may concern:

Be it known that I, ALFRED C. HOBBS, of the city of Bridgeport, county of Fairfield, and State of Connecticut, have invented a new and useful Machine for Removing the Primers from Cartridge-Shells, of which the following is a description, and which, when taken in connection with the accompanying drawings, is sufficient to enable any one skilled in the art to practice my invention.

My invention relates to an organized machine operating automatically for the purpose of removing the primers from cartridge-shells; and it consists of a mechanism for bringing the shells successively under the extracting device, mechanism for holding the shells during the piercing of the primer by the extracting device, mechanism for holding the shells during the extraction of the primers therefrom, and mechanism for piercing, extracting, and discharging said primers which it is desired to remove.

In the accompanying drawings, Figure 1 represents a side view, partly in section, of the machine when just about to descend to pierce and extract a primer from a cartridge. Fig. 2 shows a side view of the machine, partly in section, the parts being in the position for the extracting of a primer from the cartridge. Fig. 3 shows an enlarged view of a portion of the machine, partly in section, just after the primer has been pierced by the extractor. Fig. 4 shows an enlarged view, partly in section, of a portion of the machine just before the piercing of a primer by the extractor. Fig. 5 shows a bottom view of the compound plunger, and Fig. 6 shows a cross-section on the line E E of Fig. 4, some of the parts being omitted.

My machine consists of a rotating table, which may be moved automatically by the proper mechanism, (not shown,) which table is shown in Figs. 1 and 2, hereto annexed, at A. From this rotating table pins project upward, such as have for a long time been in use, and upon which pins are placed successively the cartridge-shells containing the primers which are to be removed. These pins are shown at a a a in the various drawings. Each pin is provided with an opening, a', through it, so that when primers are being removed from

cartridge-shells, which primers contain the fulminating-powder, the accidental ignition of the same will not smoke or mar the interior surface of the shell, the flash or flame being carried down through the holes a' a' in the pins a and allowed to escape through the pins and through an opening made in the frame of the machine at its base, as shown at a''. A series of pins, a, are arranged upon the table, as shown, so that as the table rotates the attendant or some automatic device may place the shells upon the pins one by one with their base upward.

Projecting upward from the base B, and attached to the main frame C of the machine, is a frame, D, as shown in the various drawings, carrying in a suitable slide a compound plunger, which plunger is caused to be reciprocated vertically by the action of the crank F, the connecting-rod G, the vibrating lever H, pivoted to the frame C at h, and the short link I, connecting one end of the beam or lever H and the compound plunger.

The compound plunger consists of an exterior hollow plunger, as shown in the various figures at J, and an interior plunger, as shown at K. Between the top of the interior plunger and the upper portion of the opening in the exterior plunger the spiral spring L is placed. This spring L continually tends to press down the interior plunger. The interior plunger is provided with two slotted keyways, and at its lower extremity with a slot and pin on one side. The two slotted keyways are shown at j and j'. The one shown at j is twice as long as the one shown at j'. Both of the slots j and j' terminate at their upper extremities on the same horizontal plane. At the lower end of the exterior plunger, J, is a slot, as shown in the various figures at b, and at b' is a pin passing through the slot b, for the purpose of operating the extracting device, as will hereinafter be more fully explained. The interior plunger is provided with a T-headed key, M, which can slide in the slot made in the interior plunger and also in the slots j and j' of the exterior plunger, and this key is continually pressed toward the right hand by the spring m, which is attached near the base of the plunger K. The interior plunger is slot-

ted near its lower extremity, as shown in the various figures at *k*. A pin, *k'*, passes through this slot, about which pin the extracting device can be turned.

5 The extracting device *N* is formed as shown in the various figures, the slot *n* being formed in it, and it is also shown as provided with a hook-shaped prolongation, *n'*, for the purpose of piercing the primers to be extracted.

10 At *O* is seen the wedge-shaped slotted adjusting-piece, adjustable by the set-screw *o*, which operates in connection with the T-head formed on the key *M*, as shown clearly in Figs. 3, 4, and 6, at *m'*, for the purpose of moving 15 said key when the machine is performing its upward stroke. The slotted wedge-shaped adjusting-piece *O* is stationary except where the operator desires to adjust it, and it is held fast to the stationary portion of the frame in which 20 the compound plunger slides. This piece *O* is slotted where the adjusting-screw passes through it, and its lower wedge-shaped end is forked, so that the T-shaped end of the key 25 *M* may be operated by it and pass within the forked prolongations.

The operation of the machine is substantially as follows: One of the cartridge-shells, with the primer to be removed being upon one of the pins *a*, as shown for example at *c*, and 30 being beneath the extracting-device, the compound plunger is, by the crank, connecting-rod, vibrating lever, and link, moved downward till the slotted base of the interior plunger, *K*, strikes upon the top of the shell. This 35 interior plunger, *K*, is slotted at its base, as shown, the slot being sufficiently narrow to rest upon the primer within the cavity in the base of the shell at both its edges. As soon as the interior plunger comes in contact with 40 the shell *c* its downward motion is stopped thereby, and thus the shell is held very firmly upon the pin, while the further motion of the mechanism causes the exterior plunger, *J*, to move down along the interior plunger, *K*, which is now stationary, and in its downward motion 45 compressing the spiral spring *L*, and, by means of the pin *b'* in the exterior plunger and the slot *n* in the extracting device *N*, causing said extracting device to rotate upon its pin *k'* and 50 force the sharpened hook-shaped prolongation *n'* into the primer to be extracted. This operation continues until the extracting device assumes the position shown in Figs. 2 and 3. When the parts have arrived in the relation 55 to one another shown in Figs. 2 and 3, the spring *m* will force the key *M* from the position shown in Figs. 1 and 4 to the position shown in Figs. 2 and 3. This will cause the key *M* to move into the slot *j'*. At the time 60 when the extractor has assumed the position shown in Figs. 2 and 3, and the key has passed into the slot *j'*, the entire downward motion of the compound plunger will have ceased, and the upward motion will commence. The key *M*, having firmly locked the exterior plunger, *J*, 65 and the interior plunger, *K*, together by means of the slots *j* and *j'* and the key *M*, the eleva-

tion of the compound plunger will cause the parts to be elevated while they bear to one another the relation shown in Figs. 2 and 3, the primer rising with the extractor, and being fastened upon its sharpened hook-shaped prolongation *n'*. While the primer is being thus withdrawn from the shell the shell is prevented from rising off the pin by reason of the stopper *P*, (shown in the various figures,) under which stopper the shell has been carried by the rotating table *A*, such stoppers being commonly used for like purposes in other machines operating upon cartridge-shells, and consisting of an L-shaped piece attached in the proper manner to the frame, and having a circular, square, or other opening through which the base of the interior plunger will pass, and through which the shell cannot pass.

When the operating devices have caused the plunger to be raised up so that the wedge-shaped forked end of the adjusting device *O* comes in contact with the T-head *m'* of the key *M*, the further upward motion of the plunger will cause the key *M* to be moved out of the slot *j'*, and as soon as the key is moved from said slot the spiral spring will force the key and the interior plunger, with the extracting device upon it, downward, moving it with 90 in the exterior plunger, and will force the extracting device to assume the position shown in Figs. 1 and 4. To allow this to take place the slot *j* is made twice as long as the slot *j'*. During this motion the sharpened hook-shaped prolongation *n'* of the extracting device *N* will be turned or rotated, so as to be within the slot *k* formed in the base of the interior plunger, *K*, and in this way the extracted primer will be forced from the hook-shaped end *n'* of the extractor *N*, and the mechanism will be in readiness to make another descending stroke. When the device is in this position, as shown in Fig. 1, it will again be moved down, and another pin having been moved under the stop device *P* by the automatic feed of the table, the primer within the cartridge resting upon this other pin will then be extracted in the way last described, and so on continually.

I have not shown the device for automatically rotating the table *A*, but as such ratchet and pawl devices are well-known it will not be necessary to here describe them.

The machine may be modified, likewise, without departing from the spirit of the invention.

The device can be used to extract primers which have been exploded equally as well as to extract primers which have not been exploded.

The operation of the parts is satisfactory, and the device is simple, requiring but a small space in which to use it, and is not liable to derangement.

I am aware of United States Letters Patent No. 233,317, dated October 19, 1880.

What I claim, and desired to secure by Letters Patent, is—

1. In a machine for extracting primers from cartridge-shells, a plunger consisting of two

parts, one carrying an extracting device pivoted thereto and constructed to pierce and catch the primer, and the other sliding independently connected to the extractor to project and retract the same, and mechanism whereby one part is moved independently of the other, and a carrier whereby the shells are brought successively beneath the plunger, substantially as set forth.

2. The combination, with the two-part plunger, of an extractor having a sharpened projection pivoted to one part, and connected to the other part to be vibrated by the sliding movement of the latter, substantially as set forth.

3. The combination, with the two-part plunger, of an extractor having a pointed projection pivoted within a slot of the carrying portion of the plunger, and arranged substantially as described, whereby the said projection is

carried beyond or drawn within the plunger as the extractor is vibrated.

4. The combination of the two parts constituting the compound plunger, the pivoted retractor carried by one part and movable there- 25 in by the other, a lock and actuating mechanism, whereby the parts are locked together after the primer is pierced and unlocked when the primer is lifted from the shell, as set forth.

5. The combination of the hollow plunger 30 portion J, inner portion K, extractor N, having a sharpened projection and pivoted to the portion K, and constructed to be vibrated by the movement of the portion J, and appliances whereby one portion is moved in respect to the 35 other substantially as set forth.
